US00D580547S

(12) United States Design Patent
Lolis et al.

(10) Patent No.: US D580,547 S
(45) Date of Patent: * Nov. 11, 2008

(54) TABLET

(75) Inventors: James Lolis, New York, NY (US); Ralf Ritter, Stapelfeld (DE)

(73) Assignee: NYCOMED GmbH, Constance (DE)

() Term: 14 Years

(21) Appl. No.: 29/282,864

(22) Filed: Jul. 31, 2007

(51) LOC (8) Cl. 28-01

(52) U.S. Cl. D24/101

(58) Field of Classification Search D24/100-104;
D28/4, 8.1, 8.2; 424/464-482, 453, 438,
424/732, 451; D1/100, 121, 125-128, 112,
D1/108; D21/440; 426/78
